 tion of Michigan

Application October 11, 1941, Serial No. 414,555

4 Claims. (Cl. 60—52)

This invention relates to power transmissions, particularly to those of the type comprising two or more fluid pressure energy translating devices, one of which may function as a pump and another as a fluid motor.

The invention is more particularly concerned with a power transmission system of the type incorporating what is termed a metering-in, flow rate control valve comprising an adjustable throttle together with a pressure responsive compensating valve for maintaining a constant pressure drop through the throttle. Valves of this character are customarily used in power transmission systems for producing a reduced "feed" rate of a machine tool slide or similar device which is hydraulically operated.

It has been found that, where the flow rate regulating valve is placed on the inlet side of the circuit, some difficulty has been experienced at the time the slide is started into a feeding movement from rest. This difficulty lies in the inability of the compensated flow control valve to immediately assume its normal regulating position. During the time interval that this requires, fluid is directed to the motor at a greater than normal rate causing the slide to jump ahead at the beginning of a feeding movement. This is particularly objectionable in machine tools where for some reason it may be necessary to stop the slide during the middle of a cut and then, if the feeding movement be resumed, the slide jumps ahead momentarily causing breaking of the cutting tool. This difficulty has been avoided in the past only by continued caution on the part of the operator to remember that when stopping the slide in the middle of a cut he must first back the tool away from the work slightly before resuming the feeding movement.

It is an object of the present invention to provide an improved circuit which overcomes this difficulty.

A further object is to provide in a power transmission system of this character a bypass valve ahead of the flow rate controlling valve which is so controlled as to maintain flow through the flow rate regulating valve even while the motor is stopped and thus cause the flow rate regulating valve to maintain its normal regulating position.

Further objects and advantages of the present invention will be apparent from the following description, reference being had to the accompanying drawing wherein a preferred form of the present invention is clearly shown.

In the drawing:

The single figure is a diagrammatic view of a power transmission system incorporating a preferred form of the present invention.

There is indicated at 10 a pump adapted to be driven by a suitable prime mover such as an

electric motor 12. The pump 10 has a suction conduit 14, for withdrawing fluid from a tank 16, and a delivery conduit 18. A relief valve 20, on pump 10, is adapted to pass fluid to tank 16 through a conduit 22 whenever a predetermined maximum pressure is exceeded in the pump.

The conduit 18 extends through a bypass valve 24 and a hydrostatic flow control valve 26 to a six-way directional valve 28 where it opens into 10 a valve bore 30 through an annular pressure port 32. Spaced along bore 30 to the right of port 32 are three annular ports 34, 36 and 38, while to the left of port 32 are corresponding ports 40, 42 and 44. A valve spool 46 mounted in bore 30, and slidable between five positions, has formed thereon three lands 47, 48 and 50 for controlling communication between the various ports. When in the position shown, lands 47, 48 and 50 block ports 42, 32 and 36, respectively. However, the pressure port 32 is open to the ports 38 and 44, which constitute tank ports, through passages 52 in valve spool 46. A hand lever 54 is connected to the left end of spool 46 for shifting it between its five positions. An end cap 56, on the right end of valve 28, has therein a spring-pressed detent 58 for releasably retaining spool 46 in each of three centermost positions. The right end of spool 46 carries a spring device 60, enclosed by end cap 56, which is adapted to shift the valve spool from either extreme position to the next adjacent position upon release of lever 54.

The ports 34 and 40 of valve 28 constitute cylinder ports and are connected by conduits 62 and 64 to the head and rod ends, respectively, of a cylinder 66. A piston 68 reciprocably mounted in cylinder 66 has a rod 70 which may be operatively connected to the work-carrying slide of a machine tool. The two tank ports 38 and 44 are connected by a conduit 72 to tank 16.

The purpose of flow control valve 26 is to provide a constant rate of flow through conduit 18 available for cylinder 66 when it is desired to operate piston 68 at a slow "feeding" rate. Valve 26 includes an adjustable throttle 74 and a hydrostatic valve 76. A control piston 78 of the latter is mounted in a cylinder 80 from which two passages 82 and 84 extend, one from each end, to opposite sides of throttle 74. A light spring 85 tends to move valve 76 to its open position. Thus it will be seen that hydrostatic valve 76 regulates fluid flow to throttle 74 in accordance with the pressure drop across the throttle in the well-known manner, thereby 50 maintaining the pressure drop substantially constant. The circuit thus far described is well known prior to this invention.

The conduit 18, between pump 10 and valve 26, passes through the bypass valve 24 and opens into a valve bore 86 thereof through an annular

port 88. A valve spool 90, slideable in bore 86, is adapted to open or close port 88 to an annular bypass port 92 spaced to the left of port 88. A pilot piston 94, smaller in diameter than spool 90 and mounted in a bore 96 in an end cap 98 on the right end of valve 24, is in axial alignment with and abuts spool 90. Piston 94 is subjected to fluid pressure from port 88 through a passage 100 extending therefrom to bore 96. The left end of bore 86 is also in communication with port 88 but through a restricted passage 102. A tank port 104 opening into bore 86 near the left end thereof is opened when spool 90 is in its righthand position, as shown, and blocked when shifted to the left. Port 104 is connected to tank 16 through a conduit 106 and a resistance valve 108 which is adapted to open only after a predetermined low pressure is exceeded at port 104. The bypass port 92 is connected by a conduit 110 to that portion of conduit 18 between flow control valve 26 and directional valve 28. An end cap 112 of valve 24 provides a fluid connection for the left end of bore 86 from which a conduit 114 extends to the ports 36 and 42 of valve 28. A check valve 113 may be interposed in conduit 110 to prevent any back flow which might occur during feed by leakage at valve 24.

A drain conduit 116 is provided for throttle 74 of valve 26 which connects to the tank conduit 72. The right end of bore 86 of valve 24 is open to tank through a conduit 118 to insure free shifting of spool 90.

In operation, with the parts in the positions shown and the motor 12 driving pump 10, fluid is withdrawn from tank 16 through conduit 14 and delivered by conduit 18 to the pressure port 32 of directional valve 28. From there the fluid is passed to tank 16 through passages 52 in valve spool 46, ports 38 and 44 and conduit 72.

Fluid in port 88 of valve 24 "bleeds" through restricted passage 102 to the left end of bore 86 where it acts over the full end area of spool 90. Passage 100 directs fluid from port 88 to the small bore 96 where it acts on piston 94. The end area of spool 90, however, is greater than that of piston 94 so valve spool 90 will be held to the right, as shown. Fluid in the left end of bore 86 cannot escape through connection 112 and conduit 114 as the latter is blocked at ports 36 and 42 of valve 28 by lands 50 and 47 nor can fluid escape to tank in sufficient quantity through port 104 and conduit 106, because of resistance valve 108, to permit spool 90 to be shifted to the left by pilot piston 94.

It will be noted that the resistance valve 108 is not necessary to maintain the valve 24 closed at this time since, if it were not present, then the fluid bleeding into the left end of bore 86 would escape to tank freely through port 104. This will permit spool 90 to shift to the left sufficiently to almost close port 104 and thus build up pressure on the left end of spool 90 and prevent it from moving farther to the left. In this way the spool 90 may be held just slightly away from its righthand position without, however, opening up port 92.

Accordingly, the bypass port 92 is blocked by spool 90, and the pump delivery must be directed to pressure port 32 of valve 28 through flow control valve 26. Any excess over that which the flow control will pass is bypassed to tank through the relief valve 20.

The hydrostatic valve 76 of valve 28 is under control of its piston 78, as effected by the pres-

sure differential between passages 82 and 84, to maintain a constant rate of flow through throttle 74. Thus, it will be seen that, even though the machine is at rest, fluid is metered to the pressure port 32, and the hydrostatic valve 76 is maintained in regulating position as distinguished from its wide-open position which it assumes when flow through the valve 26 as a whole is stopped.

To perform a feeding stroke to the left, the lever 54 of valve 28 is moved to its "feed left" position to shift spool 46 to the left. Land 48 opens port 32 to cylinder port 34 and directs the metered flow from valve 26 through conduit 62 to the head end of cylinder 66 causing piston 68 and rod 70 to move to the left at a feed rate to perform the work. When spool 46 was shifted, land 47 opened port 42 to cylinder port 40. This opens a path for fluid exhausting from the rod end of cylinder 66 through conduit 64, valve 28, conduit 114 and connection 112 to the left end of bore 86 in valve 24. From there the exhaust fluid passes through port 104, conduit 106 and resistance valve 108 to tank 16. Valve 108 maintains a low back pressure in bore 86 to hold valve spool 90 to the right. The restricted passage 102 "bleeds" a small amount of fluid from port 88 to supplement the cylinder exhaust fluid for holding spool 90 in this position.

Thus, it will be seen that piston 68 moves to the left at a constant feed rate, as determined by the setting of throttle 74, regardless of variations in resistance offered by the work, because of the constant pressure drop held by hydrostatic valve 76 across throttle 74. It will also be noted that the rate of flow from valve 26 at this time is exactly the same as before valve 28 was shifted to start piston 68 on a feed stroke. Thus, there is no jumping ahead as the piston 70 is started into feed which would otherwise occur due to the momentary increased rate of flow which occurs whenever flow is initiated through valve 26, and is due to the small but appreciable time interval required for valve 76 to move from its wide-open position to its regulating position.

If, for any reason, it becomes necessary to stop the machine during any portion of a work stroke, the lever 54 is shifted to return spool 46 to the position shown in the drawing. The resulting condition is the same as that first described.

When it is desired to continue the work stroke, lever 54 is again shifted to its "feed left" position. The constantly available metered flow from valve 26 will again be directed to the head end of cylinder 66, and the piston 68 will resume its feed rate from the same point at which it was stopped without racing or jumping. The necessity of backing the work away from the cutting tool before restarting to prevent breakage of the latter is completely eliminated.

When the feed stroke to the left is completed, piston 68 may be returned to the right on another feed stroke. To accomplish this, lever 54 is moved to its "feed right" position which shifts spool 46 to the right causing land 48 to open port 32 to cylinder port 40, and land 50 to open port 36 to cylinder port 34. The operation is the same as when feeding to the left except that the metered flow from valve 26 is directed through ports 32 and 40 and conduit 64 to the rod end of cylinder 66, while exhaust fluid passes from the head end thereof through conduit 62 and ports 34 and 36 to the conduit 114.

If no work is to be performed on the return

stroke, lever 54 is moved to the right to its "rapid return" position. This shifts spool 46 to its extreme right position where land 47 opens port 42 to port 44. The rest of the connections through valve 28 remain the same as last described. In this position, exhaust fluid from the head end of cylinder 66 passes through conduit 62, ports 34 and 36, conduit 114, ports 42 and 44 and conduit 72 directly to tank 16. As conduit 114 is connected to tank, pressure fluid in the left end of bore 86 of valve 24 is exhausted. The restricted passage 102 merely bleeds off to tank a small amount of fluid from port 88. Pressure in port 88 is transmitted through passage 100 to bore 96 causing pilot piston 94 to shift valve spool 90 to the left. Accordingly, port 88 is opened to port 92 and the pump delivery is bypassed around flow control valve 25 through conduit 110, ports 32 and 40 of valve 28 and conduit 64 to the rod end of cylinder 66. With valve 26 bypassed, piston 68 will return to the right at full speed and there stopped by returning lever 54 to the position shown in the drawing.

A rapid traverse movement to the left may be obtained in a similar manner by shifting the valve 28 to its extreme left-hand position. It will be noted that during rapid movements in either direction, flow is maintained through flow control valve 26 since valve 24 maintains a preference, so to speak, for flow through valve 26. It is only the excess of the pump delivery over and beyond the amount accepted by valve 26, which is bypassed around the valve 26 through port 92 and conduit 110.

Whenever piston 68 is stopped, whether in feed or rapid return, valve spool 90 of valve 24 will be retained in or shifted to its righthand position to direct the pump delivery through flow control valve 26. Thus it will be seen that the piston 68 may be started from any stopping point at a feed rate, regardless of its previous action, without racing or jumping.

While the form of embodiment of the invention as herein disclosed constitutes a preferred form, it is to be understood that other forms might be adopted, all coming within the scope of the claims which follow.

What is claimed is as follows:

1. In a hydraulic power transmission the combination of a pressure fluid source, a fluid motor, a directional control valve for selectively directing fluid to and from the motor for either direction of operation thereof and having a neutral position in which flow from the source is bypassed around the motor, fluid supply and return conduits connecting the source to the motor with the directional valve therebetween, a flow rate control valve interposed in the supply conduit for producing a governed flow rate therein and having a compensating valve therein of the type which opens fully whenever the flow through the rate control valve is interrupted, a supply pressure responsive bypass valve ahead of the rate control valve and connected when open to conduct fluid around the rate control valve, and means associated with said bypass valve for maintaining it closed while the directional valve is in neutral position whereby flow is maintained through the rate control valve and the compensating valve is prevented from moving fully open.

2. In a hydraulic power transmission the combination of a pressure fluid source, a fluid motor, a directional control valve for selectively direct-

ing fluid to and from the motor for either direction of operation thereof at either of two different speeds and having a neutral position in which flow from the source is bypassed around the motor, fluid supply and return conduits connecting the source to the motor with the directional valve therebetween, a flow rate control valve interposed in the supply conduit for producing a governed flow rate therein to obtain one of said speeds and having a compensating valve therein of the type which opens fully whenever the flow through the rate control valve is interrupted, a supply pressure responsive bypass valve ahead of the rate control valve and connected when open to conduct fluid around the rate control valve to obtain the other of said speeds, and means associated with said bypass valve for maintaining it closed while the directional valve is in neutral position whereby flow is maintained through the rate control valve and the compensating valve is prevented from moving fully open.

3. In a hydraulic power transmission the combination of a pressure fluid source, a fluid motor, a directional control valve for selectively directing fluid to and from the motor for either direction of operation thereof at either of two different speeds and having a neutral position in which flow from the source is bypassed around the motor, fluid supply and return conduits connecting the source to the motor with the directional valve therebetween, a flow rate control valve interposed in the supply conduit for producing a governed flow rate therein to obtain one of said speeds and having a compensating valve therein of the type which opens fully whenever the flow through the rate control valve is interrupted, a supply pressure responsive bypass valve ahead of the rate control valve and connected when open to conduct fluid around the rate control valve to obtain the other of said speeds, and means including a connection from the exhaust side of the motor during slow speed movement for maintaining said bypass valve closed against the tendency of the supply pressure to open the bypass valve during slow speed movement of the motor.

4. In a hydraulic power transmission the combination of a pressure fluid source, a fluid motor, a directional control valve for selectively directing fluid to and from the motor for either direction of operation thereof at either of two different speeds and having a neutral position in which flow from the source is bypassed around the motor, fluid supply and return conduits connecting the source to the motor with the directional valve therebetween, a flow rate control valve interposed in the supply conduit for producing a governed flow rate therein to obtain one of said speeds and having a compensating valve therein of the type which opens fully whenever the flow through the rate control valve is interrupted, a supply pressure responsive bypass valve ahead of the rate control valve and connected when open to conduct fluid around the rate control valve to obtain the other of said speeds, means including a connection from the exhaust side of the motor during slow speed movement for maintaining said bypass valve closed against the tendency of the supply pressure to open the bypass valve during slow speed movement of the motor, and additional means including a restricted bleed connection from the supply line for maintaining the bypass valve closed while the directional valve is in neutral position.

FERRIS T. HARRINGTON.
